(57) **CLAIM**

The ornamental design for a digital microscope, as shown and described.

DESCRIPTION

FIG. 1 is a front/side perspective view of a first embodiment of a digital microscope according to our new design.

FIG. 2 is a front view of the digital microscope of FIG. 1.

FIG. 3 is a back view of the digital microscope of FIG. 1.

FIG. 4 is a left side view of the digital microscope of FIG. 1.

FIG. 5 is a right side view of the digital microscope of FIG. 1.

FIG. 6 is a top view of the digital microscope of FIG. 1.

FIG. 7 is a bottom view of the digital microscope of FIG. 1.

FIG. 8 is a front/side perspective view of a second embodiment of a digital microscope according to our new design.

FIG. 9 is a front view of the digital microscope of FIG. 8.

FIG. 10 is a back view of the digital microscope of FIG. 8.

FIG. 11 is a left side view of the digital microscope of FIG. 8.

FIG. 12 is a right side view of the digital microscope of FIG. 8.

FIG. 13 is a top view of the digital microscope of FIG. 8; and,

FIG. 14 is a bottom view of the digital microscope of FIG. 8.

The bottom views and the portions depicted in broken lines are not part of the claimed design.
